UNITED STATES PATENT OFFICE

166,601

SHELL DOLL

Stanley Goldfarb, Miami, Fla.

Application December 31, 1951, Serial No. 17,879

Term of patent 3½ years

(Cl. D34—4)

To all whom it may concern:

Be it known that I, Stanley Goldfarb, a citizen of the United States, residing at Miami, in the county of Dade and State of Florida, have invented a new, original, and ornamental Design for Shell Doll, of which the following is a specification, reference being had to the accompanying drawing, forming a part hereof.

Figure 1 is a front elevational view of a shell doll showing my new design.

Figure 2 is a rear elevational view.

Figure 3 is a side elevational view.

I claim:

The ornamental design for a shell doll, substantially as shown.

STANLEY GOLDFARB.
